US00D988062S

(12) **United States Design Patent** (10) **Patent No.:** **US D988,062 S**
(45) **Date of Patent:** **** Jun. 6, 2023**

(54) **ELECTRIC GRIDDLE**

(71) Applicant: **StoreBound LLC**, New York, NY (US)

(72) Inventors: **Yiyang Zhang**, Shenzhen (CN); **Shelby Scott**, New York, NY (US); **Evan Marc Dash**, New York, NY (US)

(73) Assignee: **STOREBOUND LLC**

(**) Term: **15 Years**

(21) Appl. No.: **29/750,778**

(22) Filed: **Sep. 16, 2020**

(51) **LOC (14) Cl. 07-02**

(52) **U.S. Cl.**

USPC **D7/363**

(58) **Field of Classification Search**

(57) **CLAIM**

The ornamental design for an electric griddle, as shown and described.

DESCRIPTION

FIG. 1 is a top front perspective view of an electric griddle according to our new design;

FIG. 2 is a bottom rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawings illustrate portions of the electric griddle that form no part of the claimed design.

1 Claim, 6 Drawing Sheets
